UNITED STATES PATENT OFFICE.

KURT ALBERT, OF WIESBADEN, GERMANY.

REISSUED

SIEMENS-MARTIN FURNACE.

1,073,653.

Specification of Letters Patent. Patented Sept. 23, 1913.

Application filed December 16, 1912. Serial No. 737,110.

To all whom it may concern:

Be it known that I, KURT ALBERT, a citizen of Germany, and a subject of the King of Prussia and Emperor of Germany, residing at Wiesbaden, in the Kingdom of Prussia and Empire of Germany, have invented new and useful Improvements in Siemens-Martin Furnaces, of which the following is a specification.

10 My invention relates to furnaces for working up materials containing not only iron or ferric oxide but also volatile metals, the purpose being to recover the volatile metals in addition to manufacturing the iron.

15 When it is desired to work up materials containing both iron or ferric oxide and, in addition, volatile metals such as galvanized iron, zinkiferous calcined pyrites and the like, and simultaneously to obtain not only 20 a high-quality iron, but also the volatile metals as such or as their oxids, the furnace requisite for this purpose must be capable of developing the degree of heat which is necessary for the usual Siemens-Martin 25 process, and which can only be obtained by means of the chamber system. During the first period of the operation of the furnace, when the volatile metals, either in the form 30 of metals or their oxids, are eliminated, the waste gases or those leaving the hearth-chamber and containing such metals or their oxids, must not pass through the chambers of an ordinary Siemens-Martin furnace because the chambers would in a very 35 short time become more or less choked up and consequently either impair the working of the furnace or cause the complete stoppage of the smelting process.

The primary object of my invention is to 40 provide an improved furnace for working up such materials so constructed as to avoid the passage of the waste gases through the chambers of the furnace and which nevertheless enables the waste gases to be utilized 45 during the volatilization period. I attain this end by means of a furnace which, like the Siemens-Martin furnace, has chambers for preliminarily heating the air and gas, but is so arranged that the combustion gases 50 are able to pass through suitable, readily cleaned flues, chambers or other heat-recovering apparatus.

Several forms of my improved furnace

are represented by way of example in the accompanying drawings, wherein:

Figure 1 is a side elevation, partly in section, showing a furnace embodying one form of my invention; Fig. 2 is a top plan view thereof; Fig. 3 is a vertical longitudinal section showing another form of the invention; Fig. 4 is a horizontal section of the form shown in Fig. 3; Figs. 5 and 6 are similar views, respectively, showing still another form.

In the form of my improved furnace shown in Figs. 1 and 2 the waste gases are utilized by means of a recuperator. Hence even during the period when the gases are charged with vapors arising from the said metals or their oxids, the air for combustion is preliminarily heated, according to my invention, to such a temperature that a sufficiently high temperature is obtained in the furnace.

In the form shown in Figs. 1 and 2, F 75 is a furnace of the known open hearth type, which has the hearth room II arranged in the usual manner near the top thereof. Beneath this hearth II the usual Siemens chambers are arranged of which the inner 80 pair K², K³ serve for heating the air to be led to the hearth while the outer pair K¹, K⁴ serve for heating the combustible gas before its entrance to the hearth. The channels for guiding the combustible gas 85 to the chambers K¹, K⁴ and also the channels for guiding air directly to the air chambers K², K³ are arranged in the usual known manner and therefore are not shown in the drawings. Flues a¹, a² arranged in the 90 brickwork of the furnace F connect the hearth room II with the right and left hand gas chambers K¹, K⁴ and corresponding flues a³, a⁴ lead from said hearth room to the right and left hand air chambers K², K³. 95 The four chambers K¹, K² and K³, K⁴ are connected by conduits 1 and 1' (see Fig. 2) with a main flue b leading to a smoke stack not shown. A damper S of any known construction which may be operated from 100 the outside is arranged in the main flue b. From the left hand flue a³ another flue c branches off which leads to a recuperator R of any known construction and containing channels for the gases of combustion 105 coming from the hearth II, and other chan-

nels for the air to be heated therein before its entrance into the hearth chamber. This air to be heated enters the recuperator R through a conduit o. A fan v, may be arranged at the end of the flue d leading from the recuperator R, to produce the necessary draft in the recuperator for sucking off the gas of combustion from the hearth H and drawing in the fresh air. A damper, t, 10 similar to the damper S of the main flue b is arranged in the channel or flue c. A conduit e leading from the air channels of the recuperator R terminates in a channel f which conducts the air directly from the recuperator R to the hearth H. Another 15 conduit g branches off from said conduit e and leads to the right hand air chamber K². A damper p in the conduit f controls communication between said conduit f and the conduit e, duct f terminates in the duct f' which extends vertically upward and opens into air flue a² whereas duct g opens into air chamber K².

When the furnace is working normally 20 the gases from the hearth-chamber H pass alternately through the right hand and left hand flues a⁴, a⁵ and the air-chambers K⁴ and gas-chambers K¹ and the main flue b to the smoke stack in the usual well known 25 manner. During the volatilization of the metals in question the flue b is closed by the damper S and the waste gases flow from the hearth-chamber H through the left flue a³ and conduit c to the recuperator R, the 30 necessary draft in the recuperator being produced by the fan arranged at the flue d and not shown.

The air entering through the conduit o and preliminarily heated in the recuperator 40 R passes through the flue e to the hearth H either directly by way of the flue f, or first by way of the flue g to the right air-chamber K², where it is heated more highly 45 and thence passes to the hearth where it is used for the combustion the volatilized metals or oxids may be recovered from the waste gases in the known manner by means of dust chambers and filtration. (Cf. e. g. Schnabel, *Handbuch der Metallhuttenkunde*, second edition, Berlin, 1904, p. 289 ff.)

The preliminary heating of the air for combustion by a recuperator does not suffice, however, for producing the temperature required in the Siemens-Martin furnace, 50 whereby the process of volatilization is, of course, protracted. If the air preliminarily heated in the recuperator is conducted through one air-chamber only for heating it still more, this air-chamber is considerably cooled as the period of removing the volatile metals is a multiple of the time in which a Siemens-Martin furnace working normally is reversed and the air is caused to go through the other chamber in order to reheat the first chamber. The cooling of the

charge and nevertheless in each phase of the duration of the volatilization of the metals and also of the subsequent Martin process, and thus a considerable prolongation of the entire charge. If it is wished to obviate this prolongation of the duration of charge and nevertheless in each phase of the process to obtain the high preliminary heating of the air for combustion requisite for obtaining a hot flame, I preferably provide the Siemens-Martin furnace with two pairs of air-chambers, which enable different modes of working as desired, instead of providing a recuperator.

In Figs. 3 to 6 two forms of such a Siemens-Martin furnace with two pairs of air chambers are illustrated. Referring first to the form shown in Figs. 3 and 4 the furnace F' is of the same type as that shown in Figs. 1 and 2 and has the hearth H arranged in a similar manner. The ordinary or usual air-chambers J, J' are also arranged as in the example shown in Fig. 1 beneath the hearth H. Beside said usual air chambers a second pair of air chambers L, L' is provided. The gas chambers G and G' arranged in the usual manner are situated at the side of said auxiliary air chambers L and L'. Each of the flues a' coming from the hearth room H forks off into two flues a² and a³ which lead to the auxiliary air chambers L, L' and to the usual air chambers J, J' respectively. Conduits l² (see Fig. 4) connect the right and left hand auxiliary chambers L and L' with the main flue b leading to the smoke stack, whereas conduits l³ coming from the usual air chambers J, J' open into said conduits l². The gas chambers G, G' are connected with the main flue b by channels l⁴ as usual. All of these conduits or channels l², l³, and l⁴ contain dampers S¹ to S⁶ respectively so that each channel may be opened and closed separately.

In the use of such a furnace one pair only of air chambers is constantly used until they become stopped up, which takes place quite gradually and is distinctly perceived beforehand owing to the diminished draft in the furnace, whereupon the other pair which have been cleaned in the meantime and fettled afresh are started working, while the pair now cut out are re-established again. Or the two pairs of air-chambers may be used continuously during the same process, the one L, L' being used for the volatilization period of the metals and the other J, J' for the normal working of the furnace. In order to perform these different modes of working it is only necessary to open or close the corresponding dampers S¹ to S⁶ in the conduits l² to l⁴.

During the normal working of the furnace when the air-chambers J, J' are used, the dampers S¹, S³, S⁴ and S⁶ for the cham-

bers J, J' and G, G' are open, while the dampers S² and S⁶ for the chambers L, L' are closed. During the volatilization period, when air for combustion and combustible gas is conducted, for example, through the right-hand side to the furnace, the dampers S², S⁵ and S⁶ must be open, and after the reversal the dampers S¹, S² and S⁵ will be open and the remainder closed.

The form of the furnace illustrated in Figs. 5 and 6 very nearly resembles that just described, but the auxiliary air chambers M, M' here are not arranged under the hearth H but laterally thereof. Each auxiliary air chamber here is divided into flues by means of partitions m terminating below the entrance opening of the flues a' into said chambers M, M' and these entrance openings may be closed by dampers r, r'. This arrangement provides for cleaning of said auxiliary air chambers while the furnace is working, which can be done by closing the dampers r and r', while the waste gases are passing through the chambers G and J or G' and J'.

I claim as my invention:

1. In an improved Siemens-Martin furnace for working up masses containing iron or ferric oxide and volatile metals, the combination with a hearth chamber, air chambers and gas chambers, flues connecting the air chambers and the gas chambers with the hearth chamber; of additional independent flues leading from the hearth chamber, means for guiding the gases of combustion

through said additional flues during the volatilization period of the volatile metals and a recuperator for receiving the discharged gases.

2. In an improved Siemens-Martin furnace for working up masses containing iron or ferric oxide and volatile metals, the combination with a hearth chamber, air chambers and gas chambers, flues connecting the air chambers and the gas chambers with the hearth chamber; of an easily accessible recuperator, a flue for the waste gases, an air flue connecting said recuperator with the hearth chamber, and means for guiding the gases of combustion containing the volatile metals through said recuperator.

3. In an improved Siemens-Martin furnace for working up masses containing iron or ferric oxide and volatile metals, the combination with a hearth chamber, air chambers and gas chambers, flues connecting the air chambers and the gas chambers with the hearth chamber; of additional independent chambers, flues connecting said additional chambers with the hearth chamber, and means for guiding the gases of combustion through said additional chambers during the volatilization period of the volatile metals.

In testimony whereof I have hereunto set my hand in presence of two subscribing witnesses.

KURT ALBERT.
